UNITED STATES PATENT OFFICE

160,013

FRAME FOR FRAMED PHOTOGRAPHS FOR AUTOMATIC PHOTOGRAPHIC MACHINES

William Rabkin, New York, N. Y.

Application February 25, 1950, Serial No. 8,152

Term of patent 14 years

(Cl. D61—1)

To all whom it may concern:

Be it known that I, William Rabkin, a citizen of the United States of America, residing in the city, county, and State of New York, have invented a new, original, and ornamental Design for Frames for Framed Photographs for Automatic Photographic Machines, of which the following is a specification, reference being had to the accompanying drawing, forming part thereof.

In the drawing:

Fig. 1 is a front elevational view of a frame for framed photographs for automatic photographic machines, showing my new design;

Fig. 2 is an end elevational view;

Fig. 3 is a side elevational view; and

Fig. 4 is a rear view thereof.

The dominant feature of the present design resides in the outer configuration of the same, as seen most clearly in Fig. 1.

I claim:

The ornamental design for a frame for framed photographs for automatic photographic machines, substantially as shown and described.

WILLIAM RABKIN.
